UNITED STATES PATENT OFFICE.

ALEXANDER G. WILSON, OF CHICAGO, ILLINOIS.

VENTILATOR.

1,002,549.

Specification of Letters Patent.

Patented Sept. 5, 1911.

Application filed June 28, 1911. Serial No. 635,706.

To all whom it may concern:

Be it known that I, ALEXANDER G. WILSON, a citizen of the United States, residing at Chicago, in the county of Cook and State of Illinois, have invented a new and useful Improvement in Ventilators, of which the following is a specification.

My invention relates to an improvement in the class of ventilators constructed to 10 exhaust impure air from the interior of a car, or other inclosure provided therewith, by directing and deflecting air-currents past openings in the ventilator communicating through it with the inclosure to be ventilated.

In the accompanying drawing, Figure 1 shows my improved ventilator by a view in front elevation; Fig. 2 is a section on line 2, Fig. 1, and Fig. 3 is a section on line 3, 20 Fig. 2.

The ventilator as illustrated in the drawing and hereinafter described is of a shape especially adapting it to fit upon a rounded car-roof; but my improved construction 25 may be embodied in any of various shapes of ventilator to adapt it to different applications. It is essentially of general box-form and is best constructed of sheet-metal. The base 4 is shown curved and contains an 30 opening 5 to register with a vent-opening in a car-roof upon which the base seats and is secured. The top 6, which is shown curved like the base, is imperforate and is connected at its side-edges with those of 35 the base by imperforate outer side-walls 7, 7. Imperforate end or face-walls 8, 8 also connect the top and base but at some distance from their outer edges to form lower flanges 9, through holes 10 in which to fasten 40 down the ventilator, and overhanging ledges 11 serving the purpose hereinafter explained. The walls 8 extend short of the side-walls 7 to form the open ends of 45 air-passages hereinafter described. Inside the box thus constructed, and extending from top to bottom thereof at the opposite lateral edges of the base-opening 5, are straight walls 12, 12 having outwardly-projecting flanges 13 on their vertical edges. 50 The inner walls 12 are parallel with the outer side-walls 7 and form therewith air-passages 14 and 15 through the box. These inner side-walls are connected at their flanged edges by inner end-walls 16, 16, 55 which also extend from top to bottom of the box and have central openings 17, 17

which reach from the top short of the base to form there shields 18 for the purpose hereinafter explained; and at the side-edges of the openings the walls 16 are turned outwardly at an angle, as shown at 19, to render them deflecting-walls. The walls 12 and 16 form a central chamber within the box about the inlet-opening 5 in its base through which the passages 14 and 15 communicate with the interior of the ventilated car or inclosure by way of the chamber-openings 17.

The ventilator, in operative position, as on a car-roof with one of its walls 8 and the adjacent ends of the passages 14, 15 facing in the direction of motion of the car indicated by the arrow at 20 in Fig. 2, or on a stationary inclosure, works as follows: Air-currents striking the face-wall 8 are forcibly deflected by it laterally and rush through the passages 14 and 15. In crossing the ends of the spaces between the walls 8 and 16 these air-currents exert suction through those spaces and through the openings 17 and 5 to exhaust the impure air from the interior of the inclosure; and the force of the exhaust is enhanced by the deflecting action of the walls 16 by the tendency of their sections 19 to divert and thus obstruct or crowd the exit of the impure air through the openings 17. Moreover, the overhanging ledge 11 at the wall facing the air-currents tends to augment the force of their action by confining them against upward deflection and resultant dissipation of their force. The imperforate side-walls 7 thoroughly protect the interior of the ventilator from side-winds, with snow, rain, sleet and the like, but such winds in traversing the ends of the passages 14, 15 also exert suction thereat to exhaust impure air through the ventilator by the courses hereinbefore described; and whether air-currents be exerted directly or at any angle 100 against either the outer side or end walls, such snow, rain or other foreign matter carried into the passages 14 and 15 that may enter the spaces between the walls 8 and 16 will be deflected outwardly by the wall-sections 19 and deposit on the bottoms of said spaces behind the shields 18, which guard the openings 17 against the inward passage through them of such matter.

What I claim as new, and desire to secure by Letters Patent, is—

1. A ventilator of the character described

comprising a box having imperforate outer end and side walls forming openings between their adjacent ends, a base containing an inlet-opening, and a top, and a chamber 5 within the box about said opening formed of side-walls coöperating with said outer side-walls to form air-passages extending between said openings, and deflecting end-walls provided with openings and forming 10 with said outer end-walls spaces crossed at their ends by said passages, for the purpose set forth.

2. A ventilator of the character described comprising a box having imperforate outer end and side walls forming openings between their adjacent ends, a base containing an inlet-opening, and a top provided with ledge-forming extensions overhanging said end-walls, and a chamber within the box 15 about said opening formed of side-walls coöperating with said outer side-walls to form air-passages extending between said openings, and end-walls provided with openings 20

and forming with said outer end-walls spaces crossed at their ends by said passages, 25 for the purpose set forth.

3. A ventilator of the character described comprising a box having imperforate outer end and side walls forming openings between their adjacent ends, a base containing 30 an inlet-opening, and a top, and a chamber within the box about said opening formed of inner side-walls coöperating with said outer side-walls to form air-passages extending between said openings, and inner 35 end-walls having outwardly-deflected sections forming openings and shields at the bases of the openings, said inner end-walls forming with said outer end-walls spaces crossed at their ends by said passages, for 40 the purpose set forth.

ALEXANDER G. WILSON.
